UNITED STATES PATENT OFFICE.

LARS O. GRONDAHL, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed October 7, 1926. Serial No. 140,024.

My invention relates to railway traffic controlling apparatus that is, to apparatus for governing the passage of cars or trains along a railway. Certain forms of my apparatus are adapted particularly to the train-carried portion of a train control system wherein in the apparatus on the train is governed by energy received from the trackway, while other forms of apparatus embodying my invention are adapted for use either as part of the train-carried portion of a train control system or as part of a system for controlling wayside signals.

I will describe several forms of apparatus embodying my invention, and will then point out the novel features thereof in claims.

In the accompanying drawings, Fig. 1 is a diagrammatic view showing one form of apparatus embodying my invention and adapted for use as the train-carried portion of a train control system. Fig. 2 is a diagrammatic view showing a modified form of apparatus embodying my invention, suitable for use as the train-carried portion of a train control system and part of which is suitable for use as a portion of a system for the control of wayside signals. Fig. 2^a is a view indicating the coded impulses to which the apparatus shown in Fig. 2 is responsive. Fig. 3 is a diagrammatic view showing a modification of a portion of the apparatus shown in Fig. 2, and also embodying my invention.

Similar reference characters refer to similar parts in each of the several views.

Referring first to Fig. 1, the reference character D designates a relay which is energized alternately in opposite directions at a rate dependent upon traffic conditions in advance. Under safe traffic conditions this relay is energized alternately in opposite directions at a relatively rapid rate, whereas under unsafe traffic conditions this relay is energized alternately in opposite directions at a relatively slow rate. As here shown, the relay D is supplied with energy by the secondary of a transformer 4 the primary of which is connected with the output circuit of an amplifier 5. The input circuit of this amplifier is controlled by a receiving coil 6 which may have energy induced therein

from the trackway in any suitable manner. The relay D controls two slow-releasing relays C¹ and C² in such manner that these 55 relays are alternately energized when the relay D is energized alternately in opposite directions. That is to say, when contact 3-3^a of relay D is closed relay C² is energized, and when contact 3-3^b of relay D 60 is closed, relay C¹ is energized. The circuits for the relays C¹ and C² will be obvious from the drawing, it being understood that the reference characters B and O designate the two terminals of a suitable source of 65 current which is not shown in the drawing.

The relays C¹ and C² are so proportioned that when the relay D is operating at the rate corresponding to safe traffic conditions, which rate I will term the "proceed" rate, 70 the relays C¹ and C² remain constantly closed, that is, relay C¹ holds its front contact closed during the interval in which contact 3-3^b is open and relay C² holds its front contact closed during the interval in 75 which contact 3-3^a is open. When relay D is operating at the rate corresponding to unsafe traffic conditions, however, and which rate I will hereinafter term the "stop" rate, the periods of de-energization of relays C¹ 80 and C² are greater than the release periods of these relays, so that these relays are alternately opened. Each of these relays is also designed to pick up slowly and the pick up interval is longer than the interval 85 required for release, so that under unsafe conditions both relays are never closed simultaneously.

While relays C¹ and C² are closed, a proceed lamp G is continuously lighted, the 90 circuit for this lamp being from terminal B through front contact 7-7^a of relay C¹, front contact 8 of relay C² and lamp G to terminal O. When either relay C¹ or C² is open, a stop lamp R is lighted, because the 95 circuit for this lamp includes back contact 7-7^b of relay C¹ and back contact 9 of relay C² connected in multiple.

The reference characters A¹, A², A³, A⁴, A⁵ and A⁶, designate a series of speed governing relays, which relays are controlled by relays C¹ and C², and also by a circuit controller E which is constantly rotated at a rate corresponding to the speed of the

train. Usually the circuit controller E will be operatively connected with a wheel of the train. This circuit controller comprises a circular member of conducting material 30 having an insulation segment 10' in its periphery and co-operating with two oppositely located brushes 23 and 24. It follows that each brush engages the insulation segment 10 once for each revolution of the member 30.

While relays C¹ and C² are closed relay A¹ is energized, the circuit being from terminal B through front contact 7—7^a or relay C¹, front contact 8 of relay C², wires 31 and 16, and the left-hand half of the winding of relay A¹ to terminal O. Relay A¹ is provided with a stick circuit which passes from terminal B, through the member 30 of circuit controller E, brush 23, front contact 21 of relay A¹, and the right-hand half of the winding of this relay to terminal O. Relay A² is provided with a pick-up circuit which passes from terminal B through front contact 17 of relay A¹ and the right-hand half of the winding of relay A² to terminal O. This relay is also provided with a stick circuit which passes from terminal B through member 30 of circuit controller E, brush 24, front contact 22 of relay A², and the left-hand half of the winding of this relay to terminal O. The remaining relays of the series are controlled in the same manner as relay A². That is to say, the pick-up circuit for relay A³ includes contact 18 of relay A², and the stick circuit for relay A³ includes circuit controller E and contact 10 of relay A³. The pick-up circuit for relay A⁴ includes contact 32 of relay A³, and the holding circuit includes circuit controller E and contact 11. The pick-up circuit for relay A⁵ includes contact 12 of relay A⁴, and the stick circuit for the relay A⁵ includes circuit controller E and contact 14 of relay A⁵. The pick-up circuit for relay A⁶ includes contact 13 of relay A⁵, and the stick circuit includes circuit controller E and contact 15 of relay A⁶.

Relay A⁶ controls a brake application valve F having a winding 20, and which valve is arranged to cause an automatic application of the brakes when the winding 20 is de-energized. The main circuit for winding 20 is from terminal B, through contact 19 of relay A⁶ and winding 20 to terminal O.

The relay A³ controls a slow-release relay H, the circuit being from terminal B through front contact 25 of relay A³, front contact 30' of relay A⁶, and the winding of relay H to terminal O. When relay H is de-energized its back contact 28 closes an auxiliary pick-up circuit for relay A¹, which circuit is from terminal B through contact 29 on brake valve F, back contact 28 of relay H, wires 33 and 16 and the left-hand

half of the winding of relay A¹ to terminal O. Contact 29 is closed when the brake valve F is closed, but opened when this valve is open. When relay H is de-energized it also closes an auxiliary circuit for the winding 20 of brake valve F, if this valve is closed, this circuit being from terminal B, through contact 29, back contact 27 of relay H, and winding 20 of brake valve F to terminal O.

The operation of the apparatus shown in Fig. 1 is as follows: Assuming that the proceed indication is being received on a train, relays C¹ and C² are both continuously closed, so that the proceed lamp G is lighted, the stop lamp R is extinguished, each of the relays A¹ to A⁶ is energized by its pick-up circuit, and brake valve F is energized to prevent an automatic application of the brakes. I will now assume that the stop indication is received on the train, so that the relays C¹ and C² are alternately opened. Proceed lamp G will therefore be extinguished and the stop lamp R will be lighted. When one of the relays C¹ or C² opens, the pick-up circuit for relay A¹ will become opened, but this relay will remain energized until its stick circuit is opened by the engagement of segment 10 with a brush 23. Relay A¹ will then become de-energized and so will open at contact 17 the pick-up circuit for relay A², but the latter relay will remain energized due to its stick circuit until the segment 10 engages the brush 24. In similar manner, the remaining relays A will successively become de-energized at a rate dependent upon the speed of rotation of the circuit controller E, and so at a rate dependent upon the speed of the train. It follows that if the slow-release relay H were not provided, the brake valve F would become de-energized after the train had traveled a given distance following the receipt of a stop indication. As soon as relay A³ opens, however, relay H becomes de-energized, and if the speed of the train has been reduced to such value that relay H opens before relay A⁶ opens, the auxiliary circuit for brake valve F will be closed at contact 27 of relay H before the main circuit for this valve opens at contact 19 of relay A⁶, and an automatic application of the brakes will be prevented. Furthermore, the closing of contact 28 of relay H will re-energize relay A¹ and this will re-energize each of the remaining relays in the series A. When relay A³ becomes re-energized, relay H will remain open because its circuit includes contact 30' which does not close until relay A⁶ becomes re-energized. Relay H remains open, then, until relay A⁶ closes, and so prevents a brake application which would result if relay H were allowed to close before relay A⁶ closes. The successive de-energization of relays A will then begin

again, and when relay H again becomes de-energized, the brake application will occur or will not occur, according as the speed of the train is above or below a given 5 value, that is, according to whether relay H closes its back contacts before or after relay A⁶ becomes de-energized.

Referring now to Fig. 2, the reference character 6 designates a receiving coil in 10 which impulses are induced in accordance with the codes represented in Fig. 2^a. That is to say, one code which is represented by G and which I will term the "proceed" code, comprises groups of impulses, each group 15 being made up of three impulses separated by short time intervals, and each group of impulses being separated from the preceding and succeeding groups by relatively longer time intervals. In code P each group 20 is made up of only two impulses, whereas in group Y each group is made up of but one impulse. The circuit for coil 6 includes the winding of a microphone amplifier J, and when the impulses are short trains of alternating current waves this circuit is preferably tuned to resonance at the frequency of such alternating current by a condenser 35. The output circuit of the amplifier J includes a battery 34 and the primary of a 30 transformer 4. The secondary of transformer 4 supplies energy to a direct current relay D¹ through a rectifier 62. It follows that relay D¹ is energized at the beginning of each code impulse and is de-energized at 35 the end of each such impulse.

Relay D¹ includes a contact 63 which is closed momentarily while the relay is closing and is again closed momentarily while the relay is opening, but which contact is 40 open while the relay is closed and also while the relay is open. Relay D¹ also includes a contact finger 3 co-operating with a front contact member 3^a and a back contact member 3^b. 45 The reference characters A¹⁴, A¹⁵, A¹⁶, A¹⁷, A¹⁸ and A¹⁹ designate a series of relays which in this view are normally de-energized. These relays control slow-releasing relays K¹, K² and K³, which latter relays 50 in turn control signals G, P, Y and R.

I will first assume that the proceed code represented by G is being received in the coil 6. Upon the beginning of the first impulse of one of the code combinations relay D¹ 55 closes and in so doing contact 63 momentarily closes to energize a slow-releasing relay L, the circuit for which will be obvious from the drawing. When relay D¹ becomes closed, it will close a circuit for the winding of relay A¹⁴, which circuit is from terminal B through front contact 3-3^a of relay D¹, wire 36, contact 37 of relay L, wire 64, and the left-hand half of the winding of relay A¹⁴ to terminal O. This will cause contacts 42 60 and 47 of relay A¹⁴ to close, and the latter con-

tact completes a stick circuit for relay A¹⁴ which passes from terminal B through contact 40 of relay L, wire 41, contact 47 and the right-hand half of the winding of relay A¹⁴ to terminal O. At the end of the first 70 impulse relay D¹ will release, thereby again momentarily energizing relay L, and a circuit will now be closed for relay A¹⁵ which circuit passes from terminal B through back contact 3-3^b of relay D¹, wire 38, contact 39 of relay L, contact 42 of relay A¹⁴ and the left-hand half of the winding of relay A¹⁵ to terminal O. Contacts 43 and 48 of relay A¹⁵ will therefore close, whereupon a stick circuit for relay A¹⁵ will be closed, 80 which circuit passes from terminal B through contact 40 of relay L, contact 48 of relay A¹⁵ and the right-hand half of the winding of this relay to terminal O. The slow-acting characteristic of relay L is such as to keep this relay closed during the intervals between the impulses of a group of impulses of a code combination, so that relays A¹⁴ and A¹⁵ will remain energized during such intervals. It should be stated at 85 this point, however, that relay L releases during the interval between successive groups of impulses. Upon receipt of the second impulse of the group, relay A¹⁶ becomes energized through front contact 3-3^a 90 of relay D¹, contact 37 of relay L and contact 43 of relay A¹⁵, and at the end of the second impulse relay A¹⁷ becomes energized through back contact 3-3^b of relay D¹, contact 39 of relay L and contact 44 of relay 95 A¹⁶. The stick circuits for relays A¹⁶ and A¹⁷ include contacts 49 and 50 respectively, and these circuits will be understood from the similar circuits hereinbefore traced for relays A¹⁴ and A¹⁵. At the beginning of the 100 third impulse, relay A¹⁸ will be energized through contact 45 of relay A¹⁷, and at the end of this impulse relay A¹⁹ will be energized through contact 46 of relay A¹⁸. The stick circuits for relays A¹⁸ and A¹⁹ include 105 contacts 51 and 52 of these relays respectively, and will be understood from the foregoing without further explanation.

During the interval between the first group of impulses and the second group of 110 impulses relay L releases, thereby opening the stick circuits for all six relays A¹⁴ to A¹⁹, so that these relays become de-energized during such interval.

If the code indicated by P in Fig. 2^a is 115 being received, relays A¹⁴ to A¹⁷, inclusive, will become energized during each group of impulses and will again become de-energized during the intervals between groups; if the code indicated by Y is being received, relays 120 A¹⁴ and A¹⁵ will be energized by each impulse and will be come de-energized during the relatively long interval between impulses.

Relay K¹ is controlled by contact 53 of re- 125

lay A¹⁵. Relay K² is controlled by contact 54 of relay A¹⁷ and relay K³ is controlled by contact 55 of relay A¹⁹; the circuits for the relays K will be obvious from the drawing. It follows that all three relays K¹, K² and K³ will be energized at the end of a group of impulses corresponding to the proceed code G, that only relays K¹ and K² will be energized during the group of impulses corresponding to the code P, whereas only the relay K¹ will be energized by the impulses corresponding to the code Y. Each of these relays is sufficiently slow-acting to remain closed during the relatively long intervals between groups of impulses. When all three relays K are closed, the proceed lamp G is lighted through the front contacts 61, 59 and 56 of these relays, and a relay M¹ hereinafter referred to is energized in series with lamp G. When only relays K¹ and K² are energized, the lamp P is lighted through back contact 61 of relay K³, front contacts 60 and 57 of relays K² and K¹, respectively, and a relay M² is energized in series with lamp P. When only relay K¹ is energized, caution lamp Y is lighted through back contact 61 of relay K³, back contact 60 of relay K², front contact 58 of relay K¹, and a relay M³ is energized in series with lamp Y. When all three relays K are de-energized, the stop lamp R is lighted through back contacts 61, 60 and 58.

It should be noted that in the event of continuous supply of energy to the receiving coil 6, relay L will be de-energized so that all relays A¹⁴ to A¹⁹ will be de-energized and the stop lamp R will be lighted. Of course, the same thing is true in the event of continuous de-energization of the receiving coil 6.

When cab signals alone are desired, the apparatus thus far described is all that is needed, relays M¹, M² and M³ being omitted; and the apparatus up to this point is also suitable for use in the control of way-side signals. When used on a train, however, and it is also desired to impose speed limits corresponding to the cab indications, the relays M may be provided and these relays together with relay L, and back contacts 68, 69 and 70 on relays K, may control a series of relays A¹ to A¹³ in the following manner:

Assuming that the proceed lamp G is lighted, relay M¹ will be closed, and when relay L is closed relay A¹ will become energized by a circuit which includes contact 72 of relay L and contact 65 of relay M¹. The closing of relay A¹ completes a stick circuit for this relay through contact 21 of the relay and circuit controller E, and the closing of relay A¹ also completes at contact 17 the pick-up circuit for relay A². This operation is repeated throughout the entire series of relays A, so that all of these relays

become closed in a very short interval of time. Relay A¹³ completes at contact 172 the normal circuit for winding 20 of the brake valve F. As soon as the three impulses of the first group in the code have been completed relay L drops, and so contact 72 opens the pick-up circuit for relay A¹. Then when insulated segment 10 of circuit controller E engages brush 23, the stick circuit for this relay becomes opened, whereupon relay A¹ releases. This opens the pick-up circuit for relay A², and when segment 10 engages brush 24, the stick circuit for relay A² is broken, so that this relay releases. In similar manner, the remaining relays A are successively opened upon each half revolution of member 30 of circuit controller E. If the speed of the train is such that relay A¹³ opens before the next group of impulses begins, that is before relay L becomes energized, brake valve F will be de-energized and the brakes will be applied. If, however, the speed of the train is such that relay L becomes energized before relay A¹³ opens, all of the relays A which have been opened will become closed in a very short interval of time and the brake application will be prevented. The apparatus thus imposes a maximum speed limit when the proceed lamp G is lighted.

Assuming now that the first caution lamp P is lighted, relay M² will be energized and relay M¹ will be de-energized. Then when relay L closes, the operation will be the same as before, except that the pick-up of relays A and the release of these relays will begin with relay A⁴ and so after relay L becomes de-energized upon the completion of the second impulse of each group, a shorter distance of train movement will elapse before relay A¹³ will release. It follows that if the train is exceeding a certain speed which is lower than the speed permissible while the proceed lamp G is lighted, the brakes will be applied, whereas, if such lower speed is not exceeded, an automatic brake application will be prevented. When the second caution lamp Y is lighted, relay M³ is energized and relays M¹ and M² are de-energized, and the operation is the same as before, except that the pick-up and release of the relays A begins with relay A⁸, thereby imposing a still lower speed. Assuming now that the stop lamp R is lighted, the speed limit is determined by the time required for a slow pick-up relay N to close its front contact after the relay becomes energized. Relay N is provided with a circuit which includes a back contact 73 of relay A⁸. Upon the completion of the last code impulse prior to lighting of stop lamp R, relay A⁸ will open, thereby closing at contact 73 the circuit for relay N, and if brake valve F is closed and the speed of the train is such that this relay closes before

relay A^{13} opens, an auxiliary circuit for brake valve F will be completed from terminal B, through contact 71 of relay N, back contacts 70, 69 and 68 of relays K^1 , K^2 and K^3 , respectively, contact 29 on brake valve F, and winding 20 of this valve to terminal O. If, however, relay N does not close prior to the release of relay A^{13} , the main circuit for brake valve winding 20 will become open at contact 172, and the auxiliary circuit cannot, therefore, be closed, because it is open at contact 29. The low speed limit is therefore determined by the time required for relay N to close after this relay becomes energized.

In order to provide a constantly recurring low speed limit while the train is running under stop conditions, a relay Q is provided with a circuit controlled by front contact 79 of relay A^{13} . When relay A^{13} releases, relay Q becomes de-energized, thereby closing at contact 171 the pick-up circuit for relay A^8 , this circuit being from terminal B, through back contact 61 of relay K^8 , back contact 60 of relay K^2 , back contact 58 of relay K^1 , back contact 171 of relay Q, and the right-hand half of the winding of relay A^8 to terminal O. Relays A^8 to A^{13} , thereupon become energized, and the closing of relay A^{13} closes the circuit for relay Q, so that relay A^8 again releases and the successive opening of relays A^8 to A^{13} again takes place at a rate dependent upon the speed of the train. This process will be repeated indefinitely as long as the stop lamp R is lighted and the speed of the train remains low enough to avoid operation of the brake valve F.

Referring now to Fig. 3, I have herein shown a modified form of apparatus which may be controlled by the relays K in Fig. 2 for imposing speed limits on the train. In Fig. 3 the relays A^1 to A^{11} inclusive are controlled by relay L of Fig. 2 in such manner that these relays are picked up when relay L is energized, and are successively released only in accordance with the progress of the train when relay L is de-energized. The speed limits, however, are imposed in a somewhat different manner from Fig. 2. In Fig. 3 the relay N has a somewhat longer time interval of pick-up than the corresponding relay in Fig. 2, and this relay N determines in all instances the speed limit which is imposed on the train. The main circuit for the brake valve F includes contact 172 of relay A^{11} , as in the preceding views, whereas the auxiliary circuit for this brake valve includes front contact 71 of relay N and contact 29 operated by the brake valve F.

First assuming that the proceed lamp G is lighted, the circuit for relay N is from terminal B, through front contacts 61, 59 and 56 of relays K, back contact 74 of relay

A^1 , and the winding of relay N to terminal O. When relay L is closed, all relays A^1 to A^{11} will become closed, and when relay L releases, the relays A^1 to A^{11} will successively release. The release of relay A^1 will close contact 74 so that relay N will become energized. If the speed of the train is such that contact 71 of relay N closes before the last relay A^{11} releases, the brakes will not be applied, but if the speed of the train is such that the last relay A^{11} releases before contact 71 of relay N closes, an automatic brake application will be incurred.

If the first caution lamp P is lighted, the operation will be the same, except that the circuit for relay N will include back contact 75 of relay A^4 , so that the speed of the train is determined by the distance required for the relays A^5 to A^{11} , inclusive, to release, and this distance, of course, is less than the distance required for relays A^2 to A^{11} to release. If the second caution lamp Y is lighted, the operation is the same as before, except that the circuit for relay N will include contact 76 of relay A^6 , and so the speed of the train is determined by the distance required for relays A^7 to A^{11} , inclusive, to release. If the stop lamp R is lighted, the operation is again the same, except that the circuit for relay N includes contact 77 of relay A^8 , and so the speed of the train is determined by the distance required for relays A^9 to A^{11} to release.

In order to provide a recurring speed limit under stop conditions, relay Q is provided with a circuit including back contact 80 of relay A^{11} , so that relay Q will become energized when relay A^{11} releases. Contact 78 of relay Q, together with back contacts 61, 60 and 58 of relays K, closes an auxiliary pick-up circuit for relay A^1 , so that all of the relays A^1 to A^{11} again become energized and the successive release of these relays again occurs. Relay N does not become energized until relay A^8 releases, however, and so a constantly recurring low speed limit is imposed and the application of the brakes will depend on whether or not relay A^{11} releases before relay N closes.

Although I have herein shown and described only a few forms of apparatus embodying my invention, it is understood that various changes and modifications may be made therein within the scope of the appended claims without departing from the spirit and scope of my invention.

Having thus described my invention, what I claim is:

1. In combination on a railway train, a series of relays, means for causing successive release of said relays at a rate proportional to the speed of the train, a brake application valve set into operation when the last relay of said series releases, and means for preventing said valve from being set in-

to operation upon release of said last relay if more than a given interval of time is consumed by the release of a given number of said relays.

- 5 2. In combination on a railway train, a series of relays, means for causing successive release of said relays at a rate proportional to the speed of the train, means for beginning such release at different relays in 10 the series under different traffic conditions, and governing mechanism controlled in accordance with the time elapsing between the release of the relay which releases first and the release of the last relay in the series.
- 15 3. In combination on a railway train, a

series of relays, means for causing successive release of said relays at a rate proportional to the speed of the train, a slow acting device, means for starting operation of said device upon the release of different ones of 20 said relays depending upon traffic conditions, and governing mechanism on the train set into operation if the time required for said device to operate is greater than the time consumed by the release of all of the relays 25 subsequent to the relay which starts the operation of said device.

In testimony whereof I affix my signature.

LARS O. GRONDAHL.
